UNITED STATES PATENT OFFICE

DAVID S. JACOBUS, OF MONTCLAIR, NEW JERSEY, ASSIGNEE TO THE BABCOCK & WILCOX COMPANY, OF BAYONNE, NEW JERSEY, A CORPORATION OF NEW JERSEY

BOILER WITH FORCED RETURN CIRCULATION THROUGH FURNACE WALLS

Application filed October 31, 1927, Serial No. 229,893. Renewed June 23, 1932.

This invention relates to a boiler that is provided with an economizer and with means by which a portion of the feed water can be heated by blow-off water and introduced into the boiler without passing through the economizer. The invention will be understood from the description in connection with the accompanying drawings in which Fig. 1 is a vertical section through an illustrative embodiment of the invention taken along the line 1-1 of Fig. 2; and Fig. 2 is a view partly in section taken along the line 2-2 of Fig. 1. In the drawings reference character 4 indicates the furnace of the boiler that has water tubes along its walls, roof and floor. Fuel burners are shown at 5. The row of front wall tubes is indicated at 6, the side wall tubes at 7, the rear wall tubes at 8, and the roof tubes at 9. A U-shaped lower header 10 is located at the lower portion of the furnace and the tubes 6 are connected from the front portion of the header 10 to the upper front header 11. The rows of side wall tubes 7 connect the legs of the U-shaped header 10 to upper headers 13 along the sides of the furnace. The row of tubes 8 connects a lower header 14 to an upper header 15 and the row of roof tubes 9 connects the header 11 to the header 16.

A row of tubes 18 connects the lower header 14 to the header 19. The tubes 18 are bent so that an inclined portion of these tubes lies along the floor of the furnace and the remainder of the tubes lie along one side of an outlet passage for ashes. The front side of the U-shaped header 10 is connected by a row of tubes 20 to a header 21 that is located at the same level as the header 19, the row of tubes 20 forming one side of the outlet for ashes from the furnace. The rows of tubes may be lined with tile in the well known manner.

A pipe 22 provided with a valve 22' leads from the header 13 to a steam and water separator 25 and a pipe 23 provided with a valve 23' leads from the header 15 to the same separator. A steam pipe 26 leads from the steam space of the steam and water separator 25 to a second steam and water sep-

arator 27. A tube 28 leads from the water space of the steam and water separator 25 to a pipe 29 that is connected to the water space of the steam and water separator 27. A pipe 30 leads from the steam space of the steam and water separator 27 to the super-heater 31. Water level indicators 32 are provided for the steam and water separators 25 and 27. A float 33 is located in the steam and water separator 27 and controls the valve 34 in the feed water line 35. The feed water line 35 leads through the pipes 36 and 37 to the lower header 38 of an economizer of which the lower or heating section is shown at 39. The lower or heating section 39 of the economizer is connected as shown at 40 to the upper or steaming section 41 of the economizer and a tube 42 provided with a valve 42' leads from the upper section to the steam and water separator 25. The lower section 39 and the upper section 41 of the economizer are spaced apart and the super-heater 31 is located in this space.

The outlet conduit 45 from the economizer leads to an air heater 46 from which a conduit 47 leads to the stack. The cold air inlet for the air heater 46 is shown at 48 and the hot air outlet is shown at 49, which may lead to the combustion space of the furnace.

A heat exchanger 50 has a pipe 29 connected thereto and is provided with a valved blow-off or drain pipe 51. A branch 52 leads from the feed pipe 35 to a coil 53 inside of the heat exchanger 50 and a thermostatic control 54 of the same general type as illustrated in Patent 1,543,727 is provided in the outlet from the coil 53. The outlet from the thermostatic control 54 leads to a pipe 55 that connects the pipe 29 to a circulating pump 56. Thermometers 57, 58 and 59 may be provided to indicate the temperatures at the respective locations. The outlet 60 for the pump 56 has branches that lead to the headers 19 and 21. A by-pass 62 provided with a valve 63 is provided between the feed water pipe 36 to the economizer and the pipe 60, and a valve 64 is provided in the pipe 60 beyond the by-pass 62.

The operation is as follows: Feed water is introduced through the pipe 35 and the

amount thereof is controlled by the level of the water in the separator 27 by means of the float 33 and valve 34. The feed water passes from the pipe 35 through the pipes 36 and 37 into the heating section 39 of the economizer, thence through the pipe 40 into the steaming section 41 and through the pipe 42 into the separator 25. Steam and some water pass from the separator 25 through the pipe 26 into the separator 27, and steam passes through the pipe 30 from the separator 27 to the superheater 31, and thence to the steam main. Water passes from the separators 25 and 27 through the pipes 28 and 29 and is forced through the pipes 55 and 60 by means of the pump 56 through the headers and tubes around the furnace 4. The mixture of steam and water then passes through the pipes 22 and 23 to the separators 25 and the water is again circulated by means of the pump 56.

In order to prevent the water that is circulated through the furnace wall tubes from becoming too concentrated with impurities, some of this water may be continuously drawn off through the heat exchanger 50 by regulating the extent of opening of the valve in the pipe 51. Heat that is present in this hot water is recovered because some of the feed water passes through the branch pipe 52 and coil 53 in the heat exchanger to the pipe 55, and thence into the furnace wall tubes. The portion of the feed water that is thus heated is by-passed around the economizer so that heat is recovered from the blow-off water without loss of efficiency.

Some of the feed water will pass through the heat exchanger 50 because the pressure in the pipes 36 and 37 is greater than that in the pipe 55 because of the frictional resistance of the economizer and its connections between the pipe 37 and the separator 25. The readings of the thermometers 57, 58 and 59 indicate the temperatures at the respective points so as to guide the operator. The thermostatic control 54 regulates the amount of water that passes through the coil 53 so that when the temperature of the water leaving the coil 53 increases an increased amount of water will be permitted to pass through and when the temperature decreases, a decreased amount of water will be permitted to pass through. The thermostat control 54 may, for example, be like that shown in Fig. 1 of Patent #1,543,727. The connection 62 is provided so that when the boiler is being started up the valve 63 can be opened and water can be kept circulating through the economizer by means of the pump 56 during the starting period. The proportionate amount of water that is circulated between the economizer and the boiler tubes can be regulated by the extent of opening of the valves 63 and 64 during the starting period.

I claim:

1. The process which comprises positively circulating water only through the steam generating tubes of a boiler during normal operation and through said steam generating tubes and the economizer of the boiler during the starting up period. 70

2. The combination with a forced circulation boiler of a pump for maintaining circulation therethrough, an economizer connected to said boiler, means for feeding water to said economizer, and a separate connection from the discharge of said pump leading to said economizer to permit said pump to circulate fluid through said economizer and through said boiler simultaneously. 75

3. The combination with a forced circulation boiler of a pump for maintaining circulation therethrough, an economizer connected to said boiler, means for feeding water to said economizer, and a valve controlled connection from the discharge of said pump leading to said economizer to permit said pump to circulate fluid through said economizer and through said boiler simultaneously. 80

4. The combination with a forced circulation boiler of a pump for maintaining circulation therethrough, a steam and water separator connected to said boiler, an economizer connected to said separator, means for feeding water to said economizer, a connection for delivering part of the feed water to said pump, a blow-off connection for removing water from said separator, means for heating the feed water delivered to said pump by the blow-off water and a separate connection between said pump discharge and said economizer to permit said pump to circulate fluid through said economizer and through said boiler simultaneously. 95

5. In a boiler, steam generating tubes, economizer tubes connected to said boiler for feeding water thereto, a pump connected to the inlet and outlet ends of the generating tubes for circulating water thereto and a valved connection from the outlet side of the pump to the inlet side of the economizer tubes for circulating water through the same when starting up. 110

6. In a boiler, steam generating tubes, economizer tubes connected to said boiler for feeding water thereto, a pump connected to the inlet and outlet ends of the generating tubes for circulating water thereto and a valved connection from the outlet side of the pump to the inlet side of the economizer tubes for positively circulating water in parallel through said generator and economizer tubes when starting up. 120
